(57) **CLAIM**

The ornamental design for a housing for wireless device as shown and described.

DESCRIPTION

FIG. 1 is a perspective upper front view of the housing for wireless device.

FIG. 2 is a right side view of the housing for wireless device of FIG. 1.

FIG. 3 is a left side view of the housing for wireless device of FIG. 1.

FIG. 4 is a top view of the housing for wireless device of FIG. 1.

FIG. 5 is a bottom view of the housing for wireless device of FIG. 1.

FIG. 6 is a front view of the housing for wireless device of FIG. 1.

FIG. 7 is a rear view of the housing for wireless device of FIG. 1; and,

FIG. 8 is a perspective bottom front view of the housing for wireless device of FIG. 1.

The ornamental design which is claimed is shown in solid lines in the drawings. The broken lines showing portions of the article form no part of the claimed design.

1 Claim, 8 Drawing Sheets
